UNITED STATES PATENT OFFICE.

RICHARD E. WARDHAUGH, OF JACKSONVILLE, ILLINOIS, ASSIGNOR TO EDWARD P. ALLIS & CO., OF MILWAUKEE, WISCONSIN.

DUST-COLLECTOR.

SPECIFICATION forming part of Letters Patent No. 470,524, dated March 8, 1892.

Application filed April 28, 1888. Serial No. 272,206. (No model.)

To all whom it may concern:

Be it known that I, RICHARD E. WARDHAUGH, a citizen of the United States, residing at Jacksonville, county of Morgan, and State 5 of Illinois, have invented new and useful Improvements in Dust-Collectors, of which the following is a full, clear, and exact description.

This invention contemplates certain improvements in dust-collectors, having for its object to separate dust from air in an expeditious and thorough manner; and it consists of an approximately funnel-shaped receptacle, within which is disposed a shaft driven 10 by a wind-wheel through the current of air set up by the exhaust, said shaft carrying brushes adapted to remove the dust from the inside of the receptacle into a conveyer below, and also carrying beaters and a saucer, 15 substantially as hereinafter more fully set forth, and pointed out in the claims.

In the accompanying drawings, Figure 1 is a sectional elevation of my improved dust-collector. Fig. 2 is a plan view of the reversible saucer with its corrugated surface 20 upward.

In the embodiment of my invention I employ a funnel-shaped receptacle A, suitably disposed to receive the dust. This receptacle 25 or funnel is provided at its lower convergent end with an outwardly and downwardly flared or enlarged chamber A', its upper converging end uniting with said converging end of the receptacle or funnel and its lower flared end 30 preferably having a marginal flange a.

B is an upright shaft disposed centrally in the funnel or receptacle A, and provided with a wind-wheel b, arranged in the purified-air discharge of the funnel or receptacle, and 35 which is driven by the exhaust or centrifugal force of the current of air as it is discharged from the machine. This shaft is stepped at its lower end in a bearing or thumb-screw C, which is supported in a screw-threaded plate 40 c, held in one arm of a right-angled bracket d, depending from the funnel or receptacle A; or it (the screw C) may work directly in the bracket. The shaft B carries a brush D, which ranges with and removes the adhering 45 dust from the inner converging sides of the

funnel or receptacle A into the lower chamber A', the dust then falling or lodging in the saucer E, presently more fully referred to. This disposition of the dust is aided by extending the lower end of the brush a short 55 distance into chamber A'.

Upon the shaft B, within the chamber A', are secured a number of beaters or agitators F, which effect the discharge or delivery of the deposited dust from the saucer E. 60

The saucer E, which prevents indrafts to the lower or bottom end of the funnel or receptacle A which would interfere with the outflowing dust, is adapted to permit of the passage through it of the shaft, and is corrugated upon one side and smooth upon the other side. The saucer is also reversible to permit of using either side upward. Being removably held upon the shaft B, it may be by nuts e screwed upon the shaft, one above 70 and one below the saucer, or by means of shoulders upon the shaft. The corrugated side of the saucer is disposed upward to carry off, for instance, sawdust, &c., when the invention is used in wheat-machines, planing-mills, &c., the smooth side being placed upward in carrying off dust, &c. 75

To the upper part of the shaft B, within purified-air-outlet passage f of the funnel or receptacle A, is applied or secured a horizontal or transverse rod or bar G, upon which are carried two brushes H H to remove or clean the adhering dust from the walls of the outlet-passage f. These brushes are secured to sleeves or tubes g, which are fitted and 80 held upon the rod G by means of holding or thumb screws h.

It will be seen that by suitably manipulating the thumb-screw or bearing C, the shaft B, together with the saucer, beaters, and brush 85 B, can all, simultaneously and at one operation, be adjusted as may be required, while by means of the sleeve and thumb screw connection between the rod G and brushes H the latter can also be readily adjusted as occasion 90 may require.

It will be understood that I herein make no claim to any features forming the subject-matter of the claims contained in my application filed July 19, 1887, Serial No. 244,789. 95 100

I do not claim the combination, with the tapering separating-chamber provided with an inlet for the dust-laden air, an outlet for the purified air, and a dust-discharge opening 5 at its apex, of an enlarged dust-conduit applied to the small end of the separating-chamber and surrounding the opening in the apex thereof, nor the combination, with the tapering separating-chamber provided with an inlet 10 for the dust-laden air, an outlet for the purified air, and a dust-discharge opening at its apex, of an enlarged dust-conduit surrounding the dust-discharge opening and separated therefrom by an annular shoulder surrounding the dust-discharge opening.

Having fully described my invention, what I claim as new, and desire to secure by Letters Patent, is—

1. The combination, with the funnel or receptacle and the shaft, of the saucer applied to said shaft and reversible side for side, substantially as set forth.

2. The combination, with the funnel or receptacle and the wind-wheel shaft adjustably supported in place, of the saucer, beaters, and brush, all applied to and adjustable by means of said shaft, substantially as set forth.

3. The combination, with the funnel or receptacle and a lower outwardly and downwardly flared chamber, of the shaft carrying

beaters or agitators arranged in said chamber, substantially as set forth.

4. The combination, with the funnel or receptacle and a lower outwardly and downwardly flared chamber, of the shaft carrying 35 agitators or beaters arranged in said chamber and the saucer disposed upon said shaft just below the said chamber, substantially as set forth.

5. The combination, with the receptacle or 40 funnel having the enlarged lower end and the central shaft, of the reversible saucer smooth on one side and corrugated on the other side, substantially as specified.

6. The combination, with the funnel or receptacle and the wind-wheel, of the shaft carrying a brush or brushes arranged in the outlet-passage of said funnel or receptacle.

7. The combination, with the funnel or receptacle and the wind-wheel shaft, of the 50 brushes having applied thereto sleeves or tubes provided with thumb or holding screws and a cross bar or rod applied to said shaft and fitting in said tubes or sleeves, substantially as set forth.

RICHARD E. WARDHAUGH.
